(57) **CLAIM**

The ornamental design for a motorized curtain rail, as shown and described.

DESCRIPTION

FIG. 1 is a front-top perspective view of a motorized curtain rail showing my new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof;

FIG. 7 is a bottom plan view thereof; and,

FIG. 8 is a bottom perspective view thereof.

The broken lines are for the purpose of illustrating portions of the article that form no part of the claimed design.
